UNIVERSAL MACHINE FOR CANTING AND CIRCULAR-BENDING

August Wachter, Weingarten, Germany, assignor to the firm Maschinenfabrik Weingarten vorm. Hch. Schatz A. G., Weingarten, Germany

Application July 25, 1932, Serial No. 624,626, and in Germany August 6, 1931

2 Claims. (Cl. 153—16)

The object of the invention is a universal machine for canting and circular bending provided with a bending cheek adjustable in the vertical direction.

5 It is not possible by the known machines of this kind to carry out with one bending cheek all necessary kinds of cantings and circular bendings. If, for instance, low steps with long shanks are to be bent, which frequently occurs in the 10 construction of door-frames, one is obliged by the hitherto existing machines for canting and circular bending to affix on the bending cheek which is considerably distant from the center of the bend to be produced especially long and thin bending rails which are only applicable for a shank of short length and are not suitable for the 15 production of sharp-edged bends on account of the resiliency of the high thin bending rails.

By the present invention is accomplished, that 20 all necessary kinds of bends, especially low steps with long shanks, can be bent by a single bending machine. This is brought about in such a way, that the bending cheek is not only, as it is hitherto known, adjustably arranged in the vertical 25 direction, but also transversely to its level in a horizontal direction, so that it can be exactly adjusted by its horizontal adjustment transversely to its level on the corresponding bending lever arm to the strength and step of the sheet 30 to be bent.

The preferred form of embodiment of the invention is illustrated in the accompanying drawing, of which Fig. 1 is a partial front view of the bending cheek with its guide and adjustment device.

Fig. 2 is a horizontal section of the right part of Fig. 1 through the bending cheek, bending cheek arms, guide pieces and nuts.

Fig. 3 is a side view partially in section through 40 the right bearing side of the bending cheek according to the invention.

Fig. 4 is a vertical section through the upper cheek, lower cheek and bending cheek.

According to the drawing, the bending cheek *a* in which the bending rail *b* is fitted is adjustably guided in guide-pieces *c* within the bending cheek arms *d*. The adjustment of the bending cheek in a vertical direction is carried out by screw-spindles and nuts in a customary way.

50 According to the invention the bending cheek *a* is adjustable in a horizontal direction transversely to its level in such a manner, that two screw-collars *e* are screwed on the left and right bearing-side of the bending cheek, provided with 55 respective threads and are rotatable on the spindle-nuts *i*, provided with pivots. By means of the nuts *g* screwed on the ends of the pivots the screw-collars *e* are pressed against the bending cheek arms *d* in order to produce a rigid con-

nexion between the bending cheek *a* and the arms *d*.

For the purpose of adjusting the bending cheek in a horizontal direction the tension-nuts *g* and locking-nuts *f* must first be loosened and after 65 adjustment which is brought about by turning the screw-collars *e*, they are again tightened.

The rails or slides *c* in the bending cheek arms *d* serve for the precise guiding of the bending cheek *a* in the vertical direction as well as in the horizontal direction. The bending cheek *a* has in its front surface and at the ends thereof milled T-shaped grooves *h* (Fig. 1) in which corresponding T-shaped shoulders or lugs of the guiding piece *c* are fit, so that by this means a rigid connection 75 between the bending cheek *a* and the pieces *c* or by the latter with the bending cheek arms *d* in a longitudinal direction of the bending cheek is obtained.

In Fig. 3 of the drawing, the limits of the horizontal adjustment of the bending cheek are indicated at *l*. In full lines the cheek is shown as being adjusted, as at *l'*, for its shortest throw in a bending operation, and in dotted lines, as at *s*, for its longest throw. In Fig. 4 the operation of 85 the bending cheek is indicated with the cheek adjusted for its shortest throw, the movement of the cheek in upsetting the metal is indicated by broken lines.

Having described my invention, I claim:

1. A bending device comprising opposite supporting arms having longitudinal grooves in their inner faces, a bending cheek mounted between the arms with its ends movable in the grooves, pivot blocks adjustable longitudinally of the supporting arms, and exteriorly screw-threaded collars rotatable on the pivot blocks and engaging the cheek to adjust said cheek transversely of the grooves in the supporting arms.

2. A bending device comprising opposite supporting arms having longitudinal grooves in their inner faces, slides movable along said grooves, a bending cheek mounted between the supporting arms with its ends provided with transverse grooves, lugs projecting from the inner faces of the slides and engaging the grooves in the ends of the cheek to guide the cheek transversely of the slides, pivot blocks adjustable longitudinally of the supporting arms, and exteriorly screw-threaded collars rotatable on the pivot blocks and engaging the cheek to adjust said cheek transversely of the slides.

AUG. WACHTER.
